UNITED STATES PATENT OFFICE.

RUDOLPH HOFFMAN, OF KANKAKEE, ILLINOIS, ASSIGNOR TO SEARS, ROEBUCK AND CO.,
OF CHICAGO, ILLINOIS, A CORPORATION OF NEW YORK.

WICK-Straightening Means for Oil Heaters.

Application filed July 12, 1920. Serial No. 395,485.

To all whom it may concern:

Be it known that I, RUDOLPH HOFFMAN, a citizen of the United States, residing at Kankakee, in the county of Kankakee and 5 State of Illinois, have invented certain new and useful Improvements in Wick-Straightening Means for Oil Heaters, of which the following is a specification.

The invention relates in general to oil heaters of the type comprising a reservoir or font for the oil and a burner employing an annular or cylindrical wick mounted for up and down movement with reference to a pair of wick tubes the inner one of which 10 depends into the reservoir and serves to guide the wick in its movements. Wicks employed in heaters of this type are divided or split at their lower ends to permit of the spreading of the lower end portion of the 15 wick over the bottom of the reservoir around the inner wick tube, so that when the wick is new a substantial portion thereof is flared outwardly over the bottom of the reservoir. After the heater has been in use for a sub- 20 stantial length of time, the tendency of the outwardly flared lower end portion of the wick is to become set so as to retain its outwardly flared form. The result is that as the wick is gradually consumed in use so 25 that it becomes necessary to elevate it from time to time, the outwardly flared lower end portion thereof is carried a substantial distance above the bottom of the font; hence the heater is operative only when the supply 30 of oil in the font is maintained relatively 35 high.

The object of the present invention is to provide means of an extremely simple and yet highly efficient character for acting upon 40 the lower end portion of the wick, as the latter is gradually elevated in the use of the heater, to straighten out the outwardly flared portion causing it to assume a position as near the lower end of the font as its 45 length will permit.

In the accompanying drawings wherein I have illustrated one form of my improved wick straightening means, Figure 1 is a fragmentary vertical section through an oil 50 heater to which my invention is applied. Fig. 2 is a fragmentary side elevation of the lower end of a wick and its carrier showing the invention applied thereto.

Referring first to Fig. 1, I have shown a 55 heater comprising generally a reservoir or

font 3 having associated therewith a burner 4 comprising inner and outer wick tubes 5 and 6 which serve to guide an annular or cylindrical wick 7 in its up and down movements. The wick 7 is fixed with reference to 60 a metallic sleeve constituting a wick carrier 8 which is perforated so as to coat with a toothed wheel 9 of the usual wick raising and lowering means. 10 designates a flame spreader having means 11 for limiting the 65 upward movement of the wick with reference to the wick tubes 5 and 6. The inner wick tube 5 preferably depends to the bottom of the font 3, the latter being apertured and flanged inwardly as at 12 to receive the 70 lower end of said wick tube which is secured therein as by means of solder to form a liquid-tight joint.

The lower end portion of the wick is divided or split at diametrically opposite sides, 75 as shown at 13, to permit of the outward flaring of the lower end portion over a downwardly inclined supporting or bracing ring 14 for the inner wick tube. Said ring extends between the inner wick tube from a point a short distance above the bottom thereof to the bottom of the font at a point spaced outwardly from the lower end of the tube. The outer wick tube 6 preferably terminates in the top wall of the font being 80 secured thereto in any suitable way.

The wick straightening means, as illustrated in the present embodiment of the invention, is in the form of one or more helically coiled wire springs 15 coacting between the lower end of the carrier and the wick at a point adjacent thereto, tending 85 yieldingly to maintain the lower end portion of the wick near the bottom of the font. The opposite ends of the wick straightening 90 members are shaped so as to be capable of being detachably secured to the wick. Thus the upper end of each member is in the form of a finger 16 adapted to be entered through one of the apertures of the carrier and removably secured between the carrier and the wick as shown clearly in Fig. 1; and the lower end of the member 15 may be made in the form of a hook 17 so as to readily engage with the lower end of the wick. 95

Preferably at least two members 15 are employed, one on each side of the wick between the points 13 at which the wick is severed. By this arrangement, each of the side portions of the wick are maintained 100

105

110

at the bottom of the font immersed in the oil, and it will be observed that by reason of the fact that the members 15 are relatively fixed with reference to the wick any danger 5 that the members will coincide with the gaps formed at the points 13 in the wick is eliminated.

Moreover, it will be observed that the members 15 are capable of quick and easy 10 detachment so that being supplied with the heater, they may be removed from a wick removed from the burner after having been practically consumed, and readily applied to a new wick which is to be inserted. The 15 means is extremely simple in construction and yet effectively accomplishes the desired result.

I claim as my invention:

1. In combination with an oil reservoir, 20 a burner having a wick tube depending into the reservoir, and an annular wick surrounding said tube; straightening means for the lower end portion of the wick comprising a member acting between the lower end of 25 the wick and a point on the wick a substantial distance above the end thereof yieldingly to maintain the lower end of the wick near the bottom of the reservoir.

2. The combination with an oil reservoir, 30 a burner having a wick tube depending into the reservoir, and an annular wick surrounding said tube; of means tending to move the lower end portion of the wick toward the bottom of the reservoir including a member 35 in the form of a helically coiled wire spring carried by the wick and secured at its opposite ends to the lower end of the wick and at a point fixed with respect to the wick spaced a substantial distance above the lower 40 end thereof.

3. The combination with a reservoir, a burner having a wick tube depending into the reservoir and a wick surrounding said tube, of means tending to maintain the lower 45 end portion of the wick near the bottom of the reservoir comprising a resilient straightening member detachably secured at its upper end at a point fixed with respect to the wick a substantial distance above the lower 50 end thereof and engaging at its lower end with the lower end of the wick.

4. The combination with a reservoir, a burner having a wick tube depending into the reservoir, and a wick surrounding the 55 tube, said wick having its lower end divided to permit of the outward flaring of the lower end portion of the wick over the bottom of the reservoir; of means tending to move the lower end portion of the wick toward the bottom of the reservoir comprising a pair of resilient straightening members each secured at its upper end at a point fixed with respect to the wick a substantial 60 distance above the lower end thereof and en-

gaging at its lower end with the lower end 65 of the wick, said members being spaced substantially midway between the point of severance of the lower end portion of the wick.

5. The combination with a reservoir, a 70 burner having a wick tube, a wick surrounding said tube and having a metallic perforated carrier, and raising and lowering means for the wick including a toothed wheel 75 adapted to engage with the perforations of said carrier; of means tending to move the lower end portion of the wick toward the bottom of the reservoir comprising a resilient member having an upper end portion adapted to be inserted through one of said 80 carrier apertures between the wick and the carrier and a lower end portion in the form of a hook adapted to engage in the lower end of the wick.

6. In combination with a reservoir, a 85 burner having an annular wick depending into the reservoir, said wick being severed in its lower end portion so as to permit it to flare outwardly over the bottom of the reservoir, and straightening means for the 90 lower end portion of the wick comprising a plurality of resilient members movable with the wick and secured at their upper ends in fixed relation to the wick at a point a substantial distance above the lower end of the 95 wick and at their lower ends engaging the lower end of the wick tending to move it downwardly toward the bottom of the reservoir.

7. The combination with a reservoir and a 100 burner having a tubular wick depending into the reservoir, of spring means carried entirely independently of the reservoir and secured at its ends in fixed relation to the wick and operable to maintain the lower end 105 portion of the wick as near the bottom of the reservoir as is permitted by the length of the wick.

8. In combination with a reservoir and a burner having a wick depending into the 110 reservoir, of a pair of springs mounted upon and disposed at opposite sides of the wick to move therewith, said springs being operable to maintain the lower end portion of the wick as near the bottom of the reservoir 115 as is permitted by the length of the wick.

9. A means for straightening the tubular wick of an oil heater, comprising a member carried wholly independently of the heater reservoir and secured at its ends in fixed 120 relation to the wick and operable yieldingly to maintain the lower end portion of the wick near the bottom of the reservoir of the heater.

In testimony whereof, I have hereunto set 125 my hand.

RUDOLPH HOFFMAN.
